TRIMMING.

No. 18,930.

Patented Feb. 19, 1880

UNITED STATES PATENT OFFICE.

JOHANN C. F. EDELMANN AND ALPHONSE H. KURSHEEDT, OF NEW YORK,
N. Y., ASSIGNORS TO THE KURSHEEDT MANUFACTURING COMPANY, OF
SAME PLACE.

DESIGN FOR TRIMMING.

SPECIFICATION forming part of Design No. 18,930, dated February 19, 1889.

Application filed January 21, 1889. Serial No. 297,104. Term of patent 7 years.

To all whom it may concern:

Be it known that we, JOHANN C. F. EDELMANN and ALPHONSE H. KURSHEEDT, both of the city, county, and State of New York, have

5 invented and produced a new and original Design for Dress-Trimming, of which the following is a specification, reference being had to the accompanying photograph, forming part hereof, which is a face view of our newly-designed dress-trimming.

In the accompanying photograph, the letter A represents S-like figures. a is a longitudinal bar passing from center to center of the

figures A. b is a rosette between two figures A on the bar a, and d are sprays extending 15 from the rosettes b.

We claim—

The design for a dress-trimming, consisting of the S-like figures A, bar a, rosettes b, and sprays d, substantially as shown.

JOHANN C. F. EDELMANN,
ALPHONSE H. KURSHEEDT.
